UNITED STATES PATENT OFFICE.

CHARLES D. McARTHUR, OF PITTSBURGH, PENNSYLVANIA, ASSIGNOR TO BLOW COLLAPSIBLE STEEL CENTERING COMPANY, OF PITTSBURGH, PENNSYLVANIA, A CORPORATION OF NEW JERSEY.

TUNNEL-FORM.

1,009,848.

Specification of Letters Patent. Patented Nov. 28, 1911.

Application filed February 4, 1910. Serial No. 542,572.

To all whom it may concern:

Be it known that I, CHARLES D. McARTHUR, a citizen of the United States, residing at Pittsburgh, in the county of Allegheny and State of Pennsylvania, have invented certain new and useful Improvements in Tunnel-Forms, of which the following is a specification.

The invention relates to tunnel forms, and has for its principal objects; the provision of an improved form which can be readily assembled and carried to a new position after use; and the provision of an improved form of truck and supporting means for the form. One embodiment of the invention is illustrated in the accompanying drawings, wherein:—

Figure 1 is an end of the form, and Figure 2 is a section through the form on the line II—II of Figure 1, the truck being shown in side elevation, with the top supporting and contracting means removed.

The form itself is intended primarily for concrete tunnel work, and consists of a series of ribs to which is secured detachably sheet metal lagging so that when the ribs are in place the lagging plates can be applied one after the other commencing at the bottom, and the concrete filled in therebehind between such plates and the side of the excavation. Each rib preferably comprises an arched portion in two sections hinged together at substantially the center of the mold, and side portions which are detachably secured to the lower end of each section. With this form is used a truck comprising a body portion and an elevated platform, upon which platform the concrete is carried to position, and applied behind the plates. The sides of the truck are provided with expanding and contracting means for operating the lower sections of the mold, and the arched portion of the form is operated by means of contracting and expanding devices carried upon a removable standard placed upon the platform. These latter expanding and contracting means are not placed in position upon the platform until the lagging has all been applied, and the necessary concrete applied behind the lagging. By this arrangement the platform is left entirely free for the operation of handling the concrete, and after the concrete has set about the mold, the contracting and expanding devices carried by the truck are

utilized for operating the mold and carrying it bodily, ribs and lagging included, to a new position where the lagging is removed and the operation repeated.

Referring to the drawings; A, B, C, are the ribs, in the present instance channel beams spaced apart any convenient distance, as for instance about five feet; D, E, F, G, H, I, K, L, M, are lagging plates extending along the backs of the channels from the center of one channel to the center of the next channel; N is the truck for carrying the form, which truck is preferably made as long as the form which it is desired to carry, in some cases thirty or forty feet; and O is a removable standard provided with collapsing and supporting means.

Each of the ribs A, B and C is made in four sections, the two upper sections 1 and 2 being hinged together by means of the gusset plates 3 and 4 and extending down to the point 5, and the two lower sections 6 and 7 being detachably secured to the lower ends of the sections 1 and 2 by means of the plates 8 and 9. The lagging plates are provided along their horizontal edges with the abutting angles 9' having their flanges bolted together, and are secured at their ends to the ribs by means of the clips 10 which are bolted to the flanges of the channels. Any other desired means however might be used to secure the plates together and secure the plates to the channels.

The truck N rides upon the rails 11 and comprises a body portion 12, and a platform 13 mounted upon the supports 14. Turnbuckles 15 and 16 are provided for moving the channel sections 6 and 7 with the lagging carried thereby in and out, the outer ends of the turn-buckles being secured to the gusset plates 17 and 18, which plates are riveted to the sides of the channels. In order to slidably support the channel sections 6 and 7 from the truck, the gusset plates 17 are provided with laterally extending rollers 20 fitting slots 21 in the plates 22 carried by the platform 13. The platform 13 is provided with a flooring 23 upon which are mounted the rails 24 suitable for carrying a car for hauling the concrete, and the standards O are also placed at suitable intervals along this platform, the spacing ordinarily corresponding to the spacing of the channels. These standards are provided with guide portions 25 through which extends the

shaft 26 detachably engaging at its upper forked end the bolt 27 upon which the gusset plates 3 and 4 are pivoted. The shaft 26 is detachably connected at 28 with the shaft 5 section 29, and this latter section 29 is raised and lowered by means of the jack screw 30 mounted in the base 31. By this means provision is made for raising and lowering the arched portion of the form. The standard 10 O is merely seated upon the platform 13, and is held releasably thereupon by means of the turn buckles 32, which turn-buckles are detachably secured at their lower ends to the platform 13 by means of the pins 33. 15 The guide member 25 carries another pair of turn-buckles 34 having their outer ends in detachable engagement with the gusset plates 35 carried by the sections 1 and 2. The releasable engagement between the 20 outer ends of the turn-buckle rods and the plates is secured by means of the pins 36.

In operation the truck carrying the ribs or channels A, B and C is brought to the desired position in the excavation, and the 25 turn-buckles 15, 16 and 34 and the jack 30 are operated to position the ribs exactly as desired. The bottom lagging plates D are then secured in position upon the channels, and the standards O with their turn-buckles 34 and shaft 26 are then all removed from the platform 13, and concrete 30 is brought along the platform 13 and supplied behind the lagging plates D until it reaches the top of the plates. The next 35 lagging plates E are then positioned and the concrete filled in behind these plates. The operation is continued with the plates F, G, H, I, K, L and M until the lagging plates are all in position and the entire 40 space between the inner surface of the excavation and the outer surface of the lagging filled with concrete. The standards O may then be placed in position, and the turn-buckles 32 & 34, and the shaft 26 positioned, it being understood that the necessary bulk-heads are provided at the 45 desired points along the outer surface of the lagging to prevent the concrete from flowing out endwise. After the concrete has set, 50 the plates 8 and 9 are detached from the sections 1 and 2, and such sections 1 and 2 collapsed by means of the turn-buckles 34 and the jack screw 30. The turn-buckles 15 and 16 are then operated to collapse the 55 side sections 6 and 7 and the truck carrying the ribs and lagging may be moved forward to a new position, at which point the lagging is removed and the ribs expanded to their outer positions and secured together 60 by means of the plates 8 and 9. The standards O are then removed again, and the operation as heretofore described repeated. It will be seen from the foregoing that the 65 mold may be very easily and conveniently handled, and that by means of the remov-

able standards O plenty of room is given for handling the concrete without interference. The arrangement also provides for the freeing of the lagging from the concrete without difficulty, and for the transportation of the lagging plates to their new location. The engaging means between the plates 17 and 22 provide for a positive support of the side members 6 and 7, and serve to steady the entire apparatus and maintain it in proper position. Other advantages incident to the construction will be apparent to those skilled in the art. 70 75

Having thus described my invention and illustrated its use, what I claim as new and desire to secure by Letters Patent is the following:—

1. In combination in a tunnel form open at the bottom, a series of supporting ribs, lagging plates detachably secured to the ribs one above the other, a truck movable longitudinally of the form, collapsing means for the lower portions of the ribs carried by the truck, a working platform comprising the upper portion of the truck, and removable collapsing and lowering means for the upper portions of the ribs carried by the truck above the platform. 80 85

2. In combination in a tunnel form open at the bottom, a series of continuous collapsible supporting ribs each comprising an upper arch portion, and a lower side portion at each end thereof, lagging plates detachably secured to the ribs one above the other, a truck movable longitudinally of the 90 form, collapsing means for the side portions of the ribs, a working platform comprising the upper portion of the truck, and removable collapsing and supporting means for the arch portions of the ribs carried by the truck above the platform. 95

3. In combination in a tunnel form open at the bottom, a series of supporting ribs each comprising an upper arch portion in two sections hinged together at substantially the center of the mold and a lower side portion at the lower end of each section thereof, lagging plates detachably secured to the ribs one above the other, a truck movable longitudinally of the form, collapsing means for the side portions of the ribs, a working platform comprising the upper portion of the truck, and removable collapsing and supporting means for the arch portions of the ribs carried by the truck above the platform. 100 105

4. In combination in a tunnel form open at the bottom, a series of supporting ribs each comprising an upper arch portion in two sections hinged together and a lower side portion detachably secured to the lower end of each section thereof, lagging plates detachably secured to the ribs one above the other, a truck body movable longitudinally 110 115 of the form, collapsing means for the side portions of the ribs, a working platform comprising the upper portion of the truck, and removable collapsing and supporting means for the arch portions of the ribs carried by the truck above the platform. 120 125

4. In combination in a tunnel form open at the bottom, a series of supporting ribs each comprising an upper arch portion in two sections hinged together and a lower side portion detachably secured to the lower end of each section thereof, lagging plates detachably secured to the ribs one above the other, a truck body movable longitudinally 130 of the form, collapsing means for the side

portions of the ribs, an elevated working platform mounted upon upright supports carried by the truck body, and a standard removably mounted upon the platform and 5 provided with an elevating bar and laterally extending collapsing rods detachably secured to the ribs.

5. In combination in a tunnel form open at the bottom, a series of continuous collapsible supporting ribs, each comprising an 10 arch portion and side sections, lagging plates detachably secured to the ribs one above the other, a truck movable longitudinally of the form, collapsing means for the 15 side sections of the ribs, a working platform comprising the upper portion of the truck, and removable raising and lowering means for the ribs carried by the truck above the platform.

20 6. In combination in a tunnel form open at the bottom, comprising a series of sup-

porting ribs each comprising an upper arch portion in two sections hinged together at substantially the center of the mold and a lower side section detachably secured to the 25 lower end of each section thereof, lagging plates detachably secured to the ribs one above the other, a truck movable longitudinally of the form, collapsing means for the side sections of the ribs, a working platform comprising the upper portion of the truck, and removable raising and lowering means for the ribs carried by the truck above the platform.

In testimony whereof I have hereunto 30 signed my name in the presence of the two 35 subscribed witnesses.

CHARLES D. McARTHUR.
